UNITED STATES PATENT OFFICE

163,327

GOLF CLUB CART

William C. Rose, Jefferson City, Mo.

Application December 22, 1950, Serial No. 13,550

Term of patent 14 years

(Cl. D14—3)

To all whom it may concern:

Be it known that William C. Rose, a citizen of the United States, residing at Jefferson City, in the county of Cole, and State of Missouri, has invented a new, original, and ornamental Design for a Golf Club Cart, of which the following is a specification, reference being had to the accompanying drawing, forming part thereof.

I claim:

The ornamental design for a golf club cart, as shown.

WILLIAM C. ROSE.
